COMBINATION STRETCHING AND SQUEEZING TOOL

Frederick Sion, 104 Marilyn Court, Englewood, N.J.
Filed Feb. 19, 1962, Ser. No. 174,036
2 Claims. (Cl. 81—423)

This invention relates generally to hand tools and more particularly to new and useful improvements in a convertible hand tool of the pliers type.

An important object of the present invention is to provide a hand tool of the pliers type that is adapted selectively either to pinch or squeeze a device for compressing the device or to spread or stretch a device for extending the device, during the operation of pressing the handles toward each other.

Another object of the invention is to provide a convertible hand tool of the pliers type having a pair of superimposed or juxtaposed annular disk-shaped bodies, pivotal relative to each other, provided with radial handles, one disk-shaped body having a pair of peripheral spaced sockets disposed to one side of the pivot point of the bodies between the handles and the other disk body having a pair of peripheral spaced sockets disposed to the other side of said pivot point of the disk bodies, to receive a pair of detachable jaw members in operative position for either squeezing a device or spreading or extending a device.

A further object of the present invention is to provide a hand tool of the pliers type having a pair of superimposed or juxtaposed annular disk-shaped bodies, pivotal relative to each other, provided with radial handles, and a pair of detachable jaw members so that one and the same pair of jaw members can be used for either squeezing a device for compressing the same or spreading or stretching a device for extending the same.

Still another object of the invention is to provide a hand tool of the pliers type with pairs of spaced sockets adapted to be brought to operative position interchangeably in order to receive a pair of detachable jaw members.

Yet another object of the invention is to provide a convertible hand tool of the pliers type with a pair of detachable jaws adapted to be placed in operative position for either squeezing a device for compressing the same or stretching or spreading a device for extending the same, speedily and simply without the use of any additional tools as well as without the application of any considerable amount of skill, and which is so constructed that the jaw members are firmly and safely fastened to the handle members once they have been secured thereto so that they will not shake thereon and so that they cannot be lost.

It is also an object of the invention to provide a convertible, multi-purpose hand tool of the pliers type that is light in weight, handy in use, and simple in construction so that it can be manufactured and sold inexpensively but which is also sturdy, durable and well adapted to withstand the rough usage to which tools of this type ordinarily are subjected.

Still a further object of the invention is to provide a convertible multi-purpose hand tool of the pliers type that is adapted to be converted into a screw driver capable of supporting screw driver bits of various constructions for operating on screws of different constructions.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a top perspective view of a hand tool of the

2

pliers type, embodying one form of my invention, the jaw members being shown in closed condition.

FIG. 2 is an exploded perspective view of one-half of the tool of FIG. 1.

5 FIG. 2A is a similar view of the other half.

FIG. 3 is a spread edge view of the parts shown in FIG. 2, the jaw members being shown in operative position on the handles.

10 FIG. 4 is a front elevational view of a modified form of hand tool with the handles and jaw members in closed condition, the handles and jaw members being shown open in dot-dash lines.

15 FIG. 5 is a front elevational view of the hand tool of FIG. 4 with the jaw members converted into position for opening upon movement of the handles toward each other, as shown in dot-dash lines therein.

FIG. 6 is an enlarged top view of the top female disk-shaped body showing a fragment of the handle, the sleeve being omitted.

20 FIG. 7 is a similar view of the bottom male disk-shaped body.

FIG. 8 is an end view of the disk-shaped bodies in superimposed relation.

25 FIG. 9 is a sectional view through the center of the parts shown in FIG. 8.

FIG. 10 is a sectional view taken on line 10—10 of FIG. 8.

FIG. 11 is a sectional view taken on line 11—11 of FIG. 8.

30 FIG. 12 is a side elevational view of a set of operating jaw members embodying a modified form of the invention.

FIG. 13 is a cross-sectional view taken on the line 13—13 of FIG. 12.

35 FIG. 14 is a side elevational view of a set of operating jaws of modified form capable of use with the tool.

FIG. 15 is a front elevational view of another modified form of the invention capable of use as a screw driver.

FIG. 16 is an enlarged view looking from the top thereof, the screw driver being omitted.

40 Referring in detail to the drawings, in FIG. 1 a metal hand tool of the pliers type embodying one form of the invention is shown and designated generally by the reference numeral 20. The pliers 20 comprises a pair of superimposed circular disk-shaped body portions 22 and 24 with radiating elongated handles 26 and 28, respectively. The handles 26 and 28 are thicker than the body portions providing curved shoulders 30 and 32, respectively, on the inner ends thereof to receive the peripheries of the adjacent body portions thereby positioning the handles in the same plane as shown in FIG. 1. The handles are slightly curved to space the outer ends thereof away from each other. The surface of the handles may be rubberized as indicated at 34 to provide better gripping surfaces and to insulate the handles for use in electrical work.

55 The female disk body 22 is formed with a central opening 36, and the male disk body 24 is formed with a central externally threaded plug 38 projecting from its inner surface. An internally screw-threaded connecting sleeve 40 extends through the opening 36 in female body 22 and is threaded over the plug 38. The inner end of sleeve 40 is turned over as indicated at 42 to prevent complete withdrawal of the sleeve through the opening 36, and the inner surface of male disk body 24 is formed with an annular recess 44 around the base of the plug 38 to accommodate the sleeve 40 and the turned over end 42 thereof. A knurled finger piece or knob 46 is formed on the outer protruding end of the sleeve 40 for manipulating the sleeve. An annular flange 48 is formed on the sleeve adjacent the knob 46 adapted to engage the outer surface of the disk body 22. By turning knob 46 in the proper direction, the disk body 22 is drawn into

contact with disk body 24 by means of the flange 48 as shown in FIGS. 1 and 9.

In accordance with the present invention, in the periphery of female disk body 22 a pair of spaced sockets 50 and 52 are formed. Socket 50 is disposed parallel to the plane of and to one side of a median line 53 running vertically through the opening 36, the left-hand side as viewed in FIG. 4, being disposed close to said line. Socket 52 is disposed on the other or right-hand side of said line 53 at an acute angle to the vertical and being farther removed from the line.

A similar pair of sockets 54 and 56 are formed in the periphery of male body portion 24. Socket 54 is disposed parallel to the plane of the median line 53 and close thereto, and socket 56 is disposed at an acute angle to the vertical and farther removed from the line. Line 53 constitutes the vertical pivotal line of the disk-shaped bodies 22 and 24 as viewed in FIG. 4.

A pair of removable operating jaws 58 and 60 are provided for use with the disk body 24 and disk body 22, respectively. Each jaw has an elongated substantially triangular-shaped body portion 62 with a blunted apical pointed end 64. The other wider end 66 of the jaw is curved downwardly and outwardly forming a long smooth side edge 68 and a shorter side edge 70, the surface of which is recessed adjacent its wide end and formed with teeth 72 and is also formed with teeth 74 adjacent its narrower end and spaced from teeth 72. A non-circular stem 76 extends from the center of the wider curved end 66 and is externally shaped to conform to the shape of the sockets in the disk-shaped bodies 22 and 24. The stem is formed with opposed grooves 78 adjacent its outer free end to accommodate a split ring 80 adapted to seat in an annular groove 82 formed in each socket in the disk bodies so as to hold the stem in the socket when inserted therein.

In assembling the tool, the disk-shaped bodies 22 and 24 are placed in juxtaposed position and the sleeve 40 threaded over the plug 38 to draw the disk bodies together. The pair of jaws 58 and 60 are plugged into the selected pair of sockets in the disk bodies 22 and 24. During the insertion of the stems 76 into the sockets, the split rings 80 will snap into the grooves 82 in the sockets, holding the jaws in the sockets against displacement.

If it is desired to use the tool as an ordinary pliers for gripping or pressing purposes, the handles 26 and 28 are swung towards each other to close relationship as seen in FIG. 1. The jaws 58 and 60 are then inserted into the vertically disposed sockets 50 and 54, in disk bodies 22 and 24, respectively. This will position the jaws so that the threaded sides 70 thereof are contacting each other as shown in FIG. 1. By moving the handles away from each other the jaws may be separated in the ordinary manner and by subsequently moving the handles toward each other the jaws will be snapped together for gripping and pressing purposes.

If it is desired to use the tool for the purpose of spreading or distending a device as distinguished from exerting pressure on the device, the handles 26 and 28 are spread apart whereby the angularly disposed sockets 52 and 56 in disk bodies 22 and 24, respectively, are brought to a vertical position parallel to the center line 53, and the sockets 50 and 54 are moved to off-center position as viewed in FIGS. 4, 10 and 11. The jaws 58 and 60 are then plugged into the vertically disposed sockets 52 and 56 as shown in FIG. 5 wherein the handles 26 and 28 are shown spread apart and the jaws 58 and 60 are shown in intimate contact with each other. By moving the handles 26 and 28 toward each other, the jaws 58 and 60 will be moved away from each other as shown in dotted lines in FIG. 5 for spreading or distending a device for any desired purpose.

It will be understood that the form of the gripping portions of the jaws is immaterial. It is desirable when using the tool for spreading or distending purposes, that slim-

mer and thinner jaws be used with pointed ends such as the modified jaws 58' and 60' shown in FIG. 12. Each of the jaws 58' and 60' has an elongated conical-shaped body 62' coming to a point 64' and with a line of teeth 70' extending the length of the body. The stem 76' is similar to stem 76 of the jaws 58 and 60.

In FIG. 14 another modified pair of jaws 58a and 60a is shown. The jaw 58a has an elongated body 62a with a straight portion 84 and a curved portion 86, the curved portion being formed with teeth 70a on its inner surface. The stem portion 76a is similar to stem 76.

Jaw 60a has a straight body portion 72a and a stem 76a similar to stem 76. The body 72a is formed with an enlarged portion 88 for one-half its length. Threads 70a are formed on one long edge of the body for one-half its length.

Referring now to the modification of the invention shown in FIGS. 15 and 16, herein is shown a circular body 22x and an elongated straight radiating handle 26x. A pair of sockets 50x and 52x are formed in the periphery of the body. Socket 50x is disposed parallel to the handle 26x and socket 52x at an acute angle thereto. Socket 50x is adapted to detachably mount the shank portion 90 of a screw driver 92. The screw driver 92 may be one of many different types of screw drivers for operating on different types and constructions of screws.

The construction, manner of use and the several advantages of the improved hand tool will be readily understood. The tool is of great serviceability in practical use.

The jaws may be of different forms in accordance with the particular purpose for which the tool is to be used. Since the forms and shapes of the jaws which might be used are quite numerous, I have not undertaken to illustrate and describe all of the different constructions of jaws which might be provided for interchangeable connection with the pivotally connected members of the pliers, but have illustrated and described a few of the conventional forms of such jaws.

While I have illustrated and described the preferred embodiments of my invention, it is to be understood that I do not limit myself to the precise constructions herein disclosed and that various changes and modifications may be made within the scope of the invention as defined in the appended claims.

Having thus described my invention, what I claim as new, and desire to secure by United States Letters Patent is:

1. Pliers comprising a pair of superimposed circular disk-shaped bodies connected to each other by a pivot, integral handles radiating tangentially from the peripheries of the bodies for pivoting said bodies, said disk-shaped bodies each having a pair of spaced sockets in its periphery, one socket of each pair being parallel to a line longitudinal of the handles and passing through the pivot of the bodies, the other socket of the pair being at an acute angle to said line and disposed on the opposite side of said line from its respective one socket, and a removable jaw member selectively seated in a socket of each disk-shaped body.
2. Pliers comprising a pair of superimposed circular disk-shaped bodies connected to each other by a pivot, integral handles radiating tangentially from the peripheries of the bodies for pivoting said bodies, said disk-shaped bodies each having a pair of spaced sockets in its periphery, one socket of each pair being parallel to a line longitudinal of the handles and passing through the pivot of the bodies, the other socket of the pair being at an acute angle to said line and disposed on the opposite side of said line from its respective one socket, a removable jaw member selectively seated in a socket of each disk-shaped body, each jaw member comprising an elongated triangular-shaped body, the wide end of the body being arcuate-shaped forming a long side and a short side, threads on the short side of the body, and a stem extend-

ing from the bottom surface of the wide end adapted to be plugged into the socket.
